chinery Corporation, Flemington, N. J., a cor-
poration of New Jersey

Application September 25, 1946, Serial No. 699,120

11 Claims. (Cl. 89—1.7)

1

This invention relates to rocket launchers, and more particularly to the type of launcher disclosed in an application for United States Letters Patent Serial No. 683,674, filed July 15, 1946, in the name of W. V. Goodhue.

This type of launcher has a magazine arranged to hold a few rockets and from which the rockets are fed by gravity into firing position at one side of and far enough from the station where the magazine is loaded to permit continuous loading while the launcher is in action. The capacity of the magazine, though small, is sufficient to allow continuous firing by rapid fire in spite of any ordinary irregularities in the speed of handling of the rockets between the source of supply and the launcher.

An object of the invention is to provide a launcher having the above-mentioned characteristics and which, in addition, affords the maximum protection to the operating personnel from the hazards of the blast from a fired rocket as well as from unintentional firing.

This object is furthered in the illustrated launcher by use of tube-mounted rockets, each rocket-unit comprising a tube having electrical contact bands on its periphery and a rocket inside the tube, the bands being electrically connected to a primer for igniting the propellant in the rocket.

In order fully to utilize the advantages of this type of rocket from the safety standpoint, the illustrated launcher comprises a firing-tube having associated therewith improved rocket-tube holding means, constituting a feature of the invention, by which a flash-tight connection is made between the rocket-tube and the launcher just before and during the firing of the rocket. Thus, for purposes of firing, the rocket-tube becomes a continuation of the firing-tube in which the initial blast of the rocket is confined and directed rearwardly of the launcher away from the operating personnel. This holding means is arranged when operated in one direction to control the advance of a rocket-unit into firing position, the latter part of this movement being utilized to cause the holding means to grip the ends of the rocket-tube in flash-tight engagement as referred to above. When operated in the reverse direction, the holding means is retracted from beneath the rocket-tube whereby the latter is jettisoned after the rocket has been fired.

These operations, as well as the closing of the firing circuit, are effected in the proper timed relation by operating means in which invention

2

is to be recognized, all events in one firing cycle being carried out in response to a complete oscillation of an operator-controlled member.

Another feature of the invention resides in the provision of other means, under the control of the operator-controlled member, and having the dual purpose of holding the rocket-tube in firing position downwardly against the holding means and also cooperating with the holding means to prevent the advance of succeeding rocket-units toward the firing position whenever the holding means is retracted to jettison a rocket-tube or a misfired rocket.

These and other features of the invention will be apparent from the following detailed description and will be pointed out in the claims:

Fig. 1 is a view in perspective of an illustrative launcher embodying the invention, the launcher being viewed from a position ahead and outside of it and at the level of its mounting upon the deck of an amphibious craft;

Fig. 2 is a partial rear elevation of the launcher as set at an elevation of zero degrees;

Fig. 3 is a sectional elevation of a rocket-unit of the type intended to be fired from the illustrated launcher;

Fig. 4 is a partial side elevation of the portion of the launcher shown in Fig. 2 certain parts having been broken away and shown in section;

Fig. 5 is a detailed plan view of the blast operated latch for locking and releasing the operating lever for the rocket-tube holding means;

Fig. 6 is a rear elevation illustrating, partly in section, portions of the launcher adjacent to a rocket-unit in firing position; and

Fig. 7 is a view similar to Fig. 6 illustrating one stage in the jettisoning of a rocket-tube or a misfired rocket-unit and the advance of the succeeding rocket-unit into firing position.

Referring to Fig. 1 the illustrated launcher comprises a magazine 10 adapted to receive a plurality of rocket-units 12 which are advanced by gravity from the loading station at the upper edge of the magazine into the firing position (the position occupied by the leading or lower rocket-unit) where the rockets are fired one by one.

Each rocket-unit 12 comprises a cylindrical rocket-tube 14 (Fig. 3) in which is closely fitted a rocket 16. The rocket is held within the tube by a pair of spring clips 18, and for firing purposes the propellant in the tail section of the rocket is electrically connected to a pair of contact bands 20 which are insulated from each

other and encircle the rear end of the rocket-tube.

Each rocket-unit when in firing position is aligned with a firing tube 22 (Fig. 1) comprising forward and after sections 24, 26 which are fixed to the magazine 10. Mounted on the inner ends of the sections 24, 26 are rocket-tube holders 28, 30 respectively which are operated to control the advance of the rocket-units into firing position and then to hold the leading rocket in that position with its tube 14 in flash tight continuation with the firing tube 22. The holders 28, 30 are operated to carry out the above mentioned functions by swinging a lever 32 upward. In the final stage of this movement of the lever, a switch 34 (Fig. 2) in an electrical firing circuit is closed to fire the rocket in firing position. Thereafter, the lever 32 is moved down with the result that the holders 28, 30 are moved from beneath the rocket-tube from which a rocket has just been fired or to jettison a complete rocket-unit in case of a misfire. The construction and operation of the illustrated launcher which have been briefly outlined above will now be described in detail.

The magazine 10 comprises a latticed bottom 36 (Fig. 1), to the forward and after ends of which are fixed latticed end-plates 38, 40 respectively. A cover 42 (Fig. 2) is fixed to the upper edges of the end plates and closes the top of the magazine except for a narrow area conforming to the tapered upper ends of the end-plates (Fig. 1). Rocket-units are loaded into the magazine through this opening. To the upper surface of the bottom 36 are welded rails 44 (Fig. 4) on which the rocket-units roll under the influence of gravity in their advance to the firing position. Since the launcher will usually be elevated (although it may also be depressed) the rocket-units are prevented from sliding axially across the rails 44 by guide rails 46 which are fixed to the bottom 36 and are spaced so as to receive the rocket-units therebetween with a slight clearance.

The downwardly and outwardly sloping portions of the magazine 10 lead into a vertical portion which is closed at both sides by plates 48, 50 (Figs. 1 and 2) the outer plate 48 being latticed. Both plates have rails 52 welded thereon for purposes of reinforcement and for directing the rocket-units vertically into firing position. In this movement the rocket-units are guided endwise by vertical guides 53 which are integral with and continuations of the guide rails 46. The lower edges of the plates 48, 50 are further reinforced by having split tubes 54 welded to them.

The forward section 24 of the firing tube 22 has a flange 56 (Figs. 1 and 4) which is bolted to the end-plate 38, and a reduced collar 58 (Fig. 4) which extends inside the end-plate 38 through an opening therein. The holder 28 is mounted to rotate and slide axially on the collar 58 under the guidance of a pair of pins 60, each of which is received in a cam slot 62 formed in the holder. The pins 60 are fixed to the collar 58 diametrically opposite to each other. The inner end of the holder 28 has a lip 64 extending completely around it and having an internal diameter sufficient to receive an end of a rocket-tube 14 with slight clearance. A short extension 66 of the lip extends further beneath the rocket-tube for the purpose of preliminarily holding and positioning the rocket-tube as will be further explained below. The holder 28 also has a radially extending rib 68 which rides on the collar 58 and also provides a shoulder against which the end of the rocket-tube in firing position is seated. The rib 68 and

lip 64 together provide a socket for holding the forward end of the rocket-tube 14 in firing position.

It is to be understood that the holder 30 is symmetrical to the holder 28 in respect to both construction and mounting. That is, the holder 30 has cam slots 70, a lip 72, a lip-extension 74 and rib 76 which are exactly like the corresponding parts of the holder 28 except for being oppositely arranged. Pins 78, similar to the pins 60, are fixed to the rear section 26 of the firing tube and are received in the cam slots 70.

When the lever 32 is fully depressed, the holders 28, 30 are positioned with their lip-extensions 66, 74 in an elevated position (Figs. 2 and 7) where they hold a rocket-unit which engages them vertically above the firing position. By raising the lever 32 the holders are rotated to lower the lip-extensions and to bring them beneath the rocket-unit thereby to lower the rocket-unit and support it in alignment with the firing tube 22. The holders 28, 30 are thus operated by a pair of links 80 which are pivotally connected at 82 to lugs 83 on the holders. Each of the links 80 is pivoted at its upper end to one of a pair of levers 84, 86 which are fixed to a shaft 88. This shaft, to which the lever 32 is also fixed, is mounted to rotate in bearings formed in the lower margins of the end-plates 38, 40.

Arms 90, 92 on the outer ends of the levers 84, 86 respectively are curved concentrically with the shaft 88 and are adapted, depending upon their position as will be explained below, either to stop or permit the advance of the rocket-units along the rails 44 toward the firing position. A plunger 94 which is backed up by a spring 96 is slidably mounted in the lower end of each of the arms 90, 92. These plungers hold the rocket-tube in firing position down against the lip-extensions 66, 74 when the lever 32 is fully elevated.

When a rocket-unit is in firing position, the contact bands 20 on the rocket-tube 14 are engaged by a pair of terminals 98, 99 (Figs. 2 and 4) of an electrical firing circuit (not shown). The terminals are mounted on spring conductors 100 which are carried by a block of insulation 102 fixed to the inner side plate 50. The conductors 100 are electrically connected in series with the switch 34 which has a plunger 104 adapted to be engaged and depressed to close the switch by the lever 84 during the latter part of its downward movement. Thus, the rocket in firing position is fired in response to a complete upward movement of the operating lever 32.

Just prior to firing, the holders 28, 30 will have been cammed toward each other by the action of the pins 60, 78 in the cam slots 62, 70, respectively, to cause the ends of the rocket-tubes 14 to be firmly seated in the sockets provided by the ribs 68, 76 and lips 64, 72. A flash seal is thus established between the rocket-tube in firing position and the firing tube 22.

For purposes of both directing the initial flight of a fired rocket and also protecting the launcher and operating personnel from the initial blast, an extension tube 106 (Fig. 1) may be mounted on the forward section 24. As herein illustrated, this tube telescopes within the section 24 and has a lug 108 which fits between a pair of similar lugs 110 on the section 24. A bolt 112 extends through all the lugs and holds the extension tube 106 and the section 24 in assembled relation. A similar extension tube 114 may be fitted to the rear section 26 to insure that the discharge of the firing

tube will be exhausted into the open air clear of the launcher.

In order to prevent the unintentional jettisoning of a rocket-unit or rocket-tube, a latch 116 (Figs. 4, 5 and 6) cooperates with the forward arm 84 to prevent the operating lever 32 from being lowered unless the latch has been released either by the blast of a fired rocket, or manually as in the case of a misfire. The latch 116 is arranged to fit within a notch 118 (Fig. 6) in a boss 120 on the lever 84. The latch is also pivoted at 122 (Fig. 5) to a lever 124 which is pivoted on the end-plate 38 at 126. A spring 128 compressed between the end-plate 38 and the lever 124 normally urges the latch toward the lever 84; but after a fired rocket-unit passes beyond the firing tube a pad 130 on the lever 124 is struck by the fringe of the blast and the lever is swung so as to retract the latch 116 from the notch 118 in the boss 120. At this point, a spring 132 fixed to the lever 124 and bearing upon the latch 116 swings the latter about its pivot at 122 so that the end of the latch abuts the side of the boss 120. This movement of the latch is limited by its engagement with a shoulder 134 on the end of the lever 124. The operating lever 32 is now free to be moved and may be similarly freed by manual operation of the lever 124 in case of a misfire.

The latch 116 is re-engaged in the boss 120 by the action of a peripheral cam surface 136 on the lower side of the boss which strikes the latch during the latter part of the downward movement of the lever 84 and swings the latch about its pivot at 122 until the latch is aligned with and snaps into the notch 118 in the boss.

The launcher illustrated in Fig. 1 has been shown as mounted on the deck 138 of an amphibious craft adjacent to the port side 140 of the craft, its coaming being indicated at 142. The launcher may be elevated throughout a substantial angle as illustrated in Fig. 1 from a position of a few degrees of depression, by turning a crank 144. To permit such movement of the launcher it is mounted to pivot about a shaft 146 carried by a pair of lugs 148 which extend upwardly from a plate 150 fixed to the deck. Below and fixed to the bottom of the magazine 10 is a channel shaped section 152 from the rear end of which there extends downwardly a standard 154 having two feet which are bored to receive the shaft 146.

The above mentioned crank 144 operates an elevating mechanism comprising one screw 156 which is threaded into a second screw 158, the latter being threaded into a socket 160 the base of which is pivotally mounted on a shaft 162. This shaft is supported by lugs 164 which are fixed to the plate 150. The upper end of the screw 156 (Fig. 2) is reduced to form a shoulder on which seats a swivel block 166, the block at one side being mounted to pivot on a shaft 167 which rotates in a bearing 168 carried by the section 152. A stub shaft 169 extends from the other side of the block coaxially with the shaft 167 and is received in a hole in the section 152. The upper end of the screw 156 extends through the base of the swivel block 166 and has a bevel gear 170 fixed thereto. A second bevel gear 171 meshing with the gear 170 is fixed to the shaft 167. The above-mentioned crank 144 is received in a socket in the outer end of the shaft 167 and is fixed thereto by a taper pin 174. It is now apparent that the launcher may be elevated by turning the crank 144 so that the screw 156 turns out of the screw 158. When the limit of this movement has been reached, both screws turn together until the

limit of movement of the screw 158 out of the socket 160 has been reached.

In summarizing the operation of the launcher it will be assumed that the magazine 10 has been filled with rocket-units while the operating lever 32 is in its uppermost position. The leading rocket-unit in the magazine rests on the rails 44 against the arms 90, 92 and in a position to fall vertically toward the firing position when released by the arms. The lever 32 is next lowered to raise the arms 90, 92 above the leading rocket-unit (Fig. 7) and to permit the latter to advance toward the firing position. As soon as the leading rocket-unit is freed by the arms 90, 92 it falls onto the lip-extensions 66, 74 which at this time are in a well elevated position. The lever 32 is next raised as a result of which the lip-extensions 66, 74 are gradually lowered, as they rotate, to a position directly beneath the rocket-unit and finally support the rocket-unit in alignment with the firing tube 22. During the last stages of this movement the plungers 94 engage the upper sides of the rocket-tube 14 and yieldingly hold it against the lip-extensions with sufficient pressure to insure the alignment of the rocket-unit with the firing tube and the engagement of the terminals 98 with the contact bands 20. Also during this period the holders 28, 30 are cammed toward each other to cause the ends of the rocket-tube 14 to be seated against the ribs 68, 76. Finally, the plunger 104 is operated to close the switch 34 and at the same time the latch 116 locks the arm 84 and hence the lever 32 against further movement. Assuming the firing circuit to be closed at the usual local control switch at the firing station, the rocket in firing position will be fired upon the closing of the switch 34.

The initial blast of the fired rocket will be discharged harmlessly from the end of the tube-extension 116 into the open air well behind and away from the launcher and the operating personnel. When the rocket emerges from the forward tube-extension 106, the fringe of the blast will strike the pad 130 causing the latch 116 to be released from the arm 84. The lever 32 is now free to be moved downwardly again, and when it is so moved the combined axial and rotative movement of the holders 28, 30 causes the lips 66, 72 and the lip-extensions 66, 74 to be moved from beneath the empty rocket-tube which falls under the influence of gravity out of the launcher. A rocket-unit which misfires may similarly be jettisoned by lowering the lever 32 after the pad 130 has been manually operated to trip the latch 116. When the lip-extensions 66, 74 closely approach their uppermost positions, the arms 90, 92 release the next rocket-unit and permit it to fall onto the lip-extensions, ready to be advanced in the firing position in the next firing cycle.

Having described our invention, what we claim as new and desire to secure by Letters Patent of the United States is:

1. In a launcher for tube-mounted rockets, a firing tube comprising spaced forward and after sections disposed in alignment with each other, members mounted for movement on the adjacent ends of said sections, each of said members having a lip for supporting a tube containing a rocket in alignment with said sections, each of said members also having a shoulder adapted to engage an end of the rocket-tube, operator-controlled means for rotating said members successively to move said lips under and then from beneath the rocket-tube in firing position, and connections be-

between said members and sections for moving said shoulders into and out of flash-tight engagement with the ends of the rocket-tube in response to the rotative movement of said members.

2. In a launcher for tube-mounted rockets, a firing tube comprising forward and after sections which are spaced to receive a rocket-tube therebetween, members on said sections having shoulders and lips adapted to engage the end and peripheral surfaces respectively of a rocket-tube in firing position, operator-controlled means for rotating said members to move said lips beneath the rocket-tube in firing position and cam connections between said sections and members for moving the latter toward each other as they are rotated to cause said shoulders to form a flash seal with the ends of the rocket-tube.

3. In a launcher for tube-mounted rockets, a firing tube, rocket-tube holding means associated with said firing tube, and mechanism operable in one direction to move said holding means into flash-tight engagement with the ends of a rocket-tube in firing position, said mechanism being operable in another direction to separate said holding means from the rocket-tube whereby the latter is permitted to fall out of the launcher by gravity.

4. In a launcher for tube-mounted rockets, a ring tube, rocket-tube holding means carried by said firing tube, said holding means having annular shoulders defining recesses adapted to receive the ends of a rocket-tube in firing position, and operator-controlled mechanism for successively moving said holding means into engagement with the rocket-tube to establish a flash seal between the rocket-tube and said firing tube and then removing said holding means from beneath the rocket-tube whereby the latter is permitted to fall out of the launcher.

5. In a launcher for tube-mounted rockets, a ring tube, a magazine through which rocket units advance by gravity into firing position in alignment with said firing tube, rocket-tube holding means associated with said firing tube, said holding means having lips adapted to be engaged by the rocket-tube, operator-controlled mechanism for rotating said holding means to cause said lips successively to control the advance of a rocket-unit into firing position and to support the rocket-unit in alignment with said firing tube, and means constructed and arranged to utilize the rotative movement of said holding means to move the latter axially of said firing tube into engagement with the ends of the rocket-tube, said operator-controlled means being operable to reverse the above-mentioned movements of said holding means whereby the latter is separated from the rocket-tube and said lips are removed to one side of the rocket-tube to permit it to fall out of the launcher.

6. In a launcher for tube-mounted rockets, a firing tube, a magazine through which rocket units advance by gravity into alignment with said firing tube, rocket-tube holders mounted for rotative and axial movement on said firing tube, said holders having lips adapted to support a rocket-unit in firing position with the ends of the rocket-tube adjacent to and in alignment with the holders, means for oscillating said holders move said lips from beneath the rocket-tube in firing position into the path of the succeeding rocket-unit and then back to their original positions, and means for moving said holders axially

in synchronism with their rotative movements first away from the rocket-tube in firing position and then in the opposite direction to grip the ends of the succeeding rocket-tube in firing position.

5. 7. In a launcher for rockets, a magazine adapted to hold a plurality of rocket-units each consisting of a tube having a rocket mounted therein, a firing tube, holders for supporting a rocket unit in alignment with said firing tube, means for oscillating said holders from beneath a rocket-unit in firing position into the path of movement of the succeeding rocket thereby to jettison the rocket-tube in firing position and control the advance of the succeeding rocket-unit into firing position.

10. 8. In a rocket launcher, a magazine from which rocket-units are advanced by gravity into firing position, holding means for supporting a rocket-unit in firing position, said holding means being mounted for movement from beneath the rocket-unit in firing position to jettison that rocket, mechanism for operating said holding means, said mechanism comprising a member mounted for movement between a jettisoning and a firing position, a latch for locking said member in its firing position, and means operated by the blast from a fired rocket for releasing said latch.

20. 9. In a rocket launcher, a magazine from which rocket-units are advanced one by one into firing position, holding means for supporting a rocket-unit in firing position, mechanism for operating said holding means to release the rocket-unit thereon whereby that rocket-unit is jettisoned, said mechanism comprising a lever mounted to swing between a firing and a jettisoning position, a latch cooperating with said lever to lock the latter in its firing position, and latch-tripping means comprising a pad arranged to intercept the blast from a fired rocket and disengage said latch from said lever.

30. 10. In a rocket launcher, a magazine from which rocket-units are advanced by gravity into firing position, holding means for supporting a rocket-unit in firing position, a member mounted for movement into engagement with the rocket-unit in firing position to hold that rocket-unit against said holding means and then away from the said rocket-unit, and connections between said member and holding means for retracting said holding means from beneath the rocket-unit in firing position when said member is moved away from the rocket-unit.

40. 11. In a launcher for tube-mounted rockets, holders for supporting a tube containing a rocket in firing position, a magazine from which rocket-units are advanced by gravity into firing position, said holders being mounted for retractive movement from beneath the rocket-tube in firing position to jettison that rocket-tube and into the path of the next succeeding rocket-unit in said magazine whereby feeding movement of the latter rocket-unit into firing position is prevented while said holders are retracted, and operator-controlled means for operating said holders, said means comprising a lever, a link connecting said lever and holders, and an arm carried by said lever, said arm being constructed and arranged to interrupt the advance of the said next succeeding rocket-unit until said holders have been moved into the path of the last-mentioned rocket-unit.
